CLAIM

The ornamental design for a controller, as shown and described.

DESCRIPTION

FIG. 1 is a first perspective view of a controller showing a first exemplary embodiment of our new design.

FIG. 2 is a second perspective view of the controller shown in FIG. 1.

FIG. 3 is a third perspective view of the controller shown in FIG. 1.

FIG. 4 is a fourth perspective view of the controller shown in FIG. 1.

FIG. 5 is a front view of the controller shown in FIG. 1.

FIG. 6 is a rear view of the controller shown in FIG. 1.

FIG. 7 is a left side view of the controller shown in FIG. 1.

FIG. 8 is a right side view of the controller shown in FIG. 1.

FIG. 9 is a top view of the controller shown in FIG. 1; and, FIG. 10 is a bottom view of the controller shown in FIG. 1. The controller shown in FIGS. 1-10 illustrates a first embodiment of our novel design suitable for use with a right hand. Our novel design also includes a second embodiment for use with the left hand, which is mirror symmetrical to FIGS. 1-10 and therefore not separately illustrated.

The broken lines shown in the figures represent portions of the controller that form no part of the claimed design.

The thin solid lines shown in the figures represent contours only and do not illustrate an ornamentation or decoration on the surface of the controller.
